[57] **CLAIM**

The ornamental design for a “bathroom-cabinet with two sets of shelves”, as shown and described.

DESCRIPTION

FIG. 1 is a front elevational view of a bathroom-cabinet with two sets of shelves showing my new design, with the right door in an opened position;

FIG. 2 is a front elevational view thereof, with the doors in a closed position;

FIG. 3 is a top plan view thereof, with the right door in an opened position;

FIG. 4 is a bottom plan view thereof, with the doors in an opened position; and,

FIG. 5 is a left side elevational view thereof, with the doors in a closed position.

It is understood that the portions of the upper interior horizontal surface of the article not shown have not been claimed.
